UNITED STATES PATENT OFFICE.

HUGH MACRAE, OF WILMINGTON, NORTH CAROLINA.

STILL OR RETORT.

1,268,742.

Specification of Letters Patent.

Patented June 4, 1918.

Application filed March 28, 1918. Serial No. 225,371.

To all whom it may concern:

Be it known that I, HUGH MACRAE, a citizen of the United States, residing at Wilmington, in the county of New Hanover, State of North Carolina, have invented certain new and useful Improvements in Stills or Retorts, of which the following is a description, reference being had to the accompanying drawings, forming a part hereof.

10 My invention relates to retorts or stills for destructive distillation of resinous or other wood or other non-liquid material capable of being introduced into the retort or still in fragments or pieces, and my invention has for its object to provide a retort or still which will be adapted to continuous use; that is, will be adapted to permit fresh material to be introduced and exhausted material to be removed at the same time and without waiting to cool down the retort or still. A further object of my invention is to provide a retort or still in which a part of the contents may be subjected to the heat necessary to drive off the more volatile products without causing destructive distillation while another part of the contents is being subjected to a higher heat, and to provide a retort or still in which material which has been subjected to the heat necessary to drive off the more volatile products may be transferred to another part of the retort or still where it may be subjected to higher heat, from which part of the retort or still it may be subsequently transferred to another part of the still and thus subjected to still higher heat to drive off the last of the liquid products and convert the residue into charcoal.

With these and other objects hereinafter described in view of my invention consists in the construction and combination of elements hereinafter described and particularly pointed out in the claims.

Referring to the drawings,

45 Figure 1 is a vertical central sectional view of a retort or still embodying my invention.

Figs. 2 and 3 are horizontal sectional views on lines *a—a* and *b—b* respectively of Fig. 1, and

50 Fig. 4 is a detail vertical sectional view showing the means for operating the doors between the compartments.

In the drawings, 1 indicates the outer wall of a retort or still, here shown as cylindrical and arranged with its axis vertical. At its upper end the retort or kiln is provided with a charging hopper 2, into which the material to be subjected to distillation may be deposited. At its lower end the retort or still is provided with a discharge funnel 3, preferably arranged to lead to one side of the retort or still and arranged to discharge into a car 4. The retort or still is divided by horizontal partitions 5 and 6 into three parts or compartments 7, 8 and 9. These partitions may be more or less than two in number, dividing the retort or still into two, three or more compartments. At the top between the upper compartment 7 and the charging hopper 2, is a partition 11, and at the bottom between the lower compartment 9 and the discharge funnel 3 is a partition 10. Each of the partitions 5, 6, 10 and 11 is provided with one or more openings, which may be closed by a door. One of these partitions is shown in Fig. 3 in which 12 indicates the openings and 13 the doors for closing them, these doors being arranged to rotate on a central tube 14, and being connected together to a ring 15, which is provided with a rack 16 with which meshes a gear 17 on a horizontal shaft 18, which extends through the outer wall of the retort and is provided at its outer end with a hand wheel 19 for operating it. Any other form of closing device may be used, it being essential only that the partitions be provided with one or more openings of sufficient size to permit the material to be subjected to distillation to pass through it and be also provided with means for closing the opening or openings. Each of the upper compartments is provided near its upper end with an off-take 20 for drawing off the volatile products of distillation, and preferably with a second off-take 20' near its lower end, and the upper compartments are provided with means for heating the material to be subjected to distillation. Any convenient heating means may be employed, the means here shown being concentrically arranged heating coils 21 and 22, which are each provided with intakes 23 and outlets 24 for the inflow and outflow of liquid heating medium, preferably a heavy

oil which is non-volatile, at the temperatures necessary to effect the distillation. The upper compartments are also preferably provided with a coil of pipe 25, having openings or perforations in it, through which steam may be discharged if desired into the compartments to aid in or modify the action of the heating coils in drawing off the products desired.

10 The partitions 5, 6, 10 and 11 should be as nearly non-heat-conducting as they can be practically made, either by the use of non-conducting material, such as mineral wool, asbestos or similar material, or by being 15 constructed in any other preferred manner to prevent the transfer of heat from one compartment to another.

10 The lowest compartment is preferably without heating means, so as to permit material which has been heated to the point of carbonization to cool, so that it may be discharged into the funnel 3 without danger of its taking fire.

15 The outer wall 1 is preferably formed double, with the space between the two sheets of which it is formed packed with non-conducting material, such as mineral wool, in the compartment which forms the wall of the upper compartment.

20 In the part which forms the wall for the lowest compartment this space is left empty to form a water jacket, with inlet 30 and outlet 31.

25 In operation the material to be subjected to distillation is fed into the hopper 2, and the doors in the partition 11 being opened, drops through the openings into the upper compartment 7 and, the compartment being filled, the doors in the partition 11 are closed. Heat being supplied to this compartment and, the heat being regulated to the proper degree, the more volatile products, such as turpentine, if the retort or still is to be used for the distillation of pine 30 wood, are driven off and led away through the off-take of the compartment to suitable condensing apparatus (not shown). When the distillation has continued, either with or without the use of steam, either wet or super-heated, until the turpentine has been driven off, either completely, or as completely as is found practicable, the doors in partition 5 are opened and the material in the upper compartment is allowed to fall through the 35 openings in the partition into compartment 8, and when compartment 7 is thus emptied the openings in the partition are closed. The material, without losing heat, is then subjected in compartment 8 to heat sufficiently high to cause destructive distillation and the drawing off of the products which are volatile at such high temperatures. The heat may be increased by successive stages,

or otherwise, to the point at which the wood is carbonized, and when this operation is 65 complete the doors in partition 6 are opened and the charcoal and other residues, if any, remaining in the compartment are allowed to fall into the lowest compartment, where it is allowed to cool.

70 As soon as the upper compartment is emptied of its contents into the middle compartment a fresh charge of material is introduced into the upper compartment and the distillation process in the two compartments 75 is preferably so timed that when the distillation in the one is completed the distillation in the other is completed, so that as soon as the middle compartment is emptied it may be refilled from the upper compartment and 80 the upper compartment may be refilled from the charging hopper.

Having thus described my invention, what I claim and desire to secure by Letters Patent is:

85 1. A vertically arranged retort or still comprising an outer wall, a partition extending across the interior of the retort or still having openings and means for closing them, said partition separating the retort 90 or still into upper and lower compartments, heating pipes for heating the compartments, means for supplying a heating medium to the heating pipes of the different compartments independently, and separate offtakes for the 95 products of distillation leading from the different compartments, the offtake for the lower compartment leading from near the partition at the upper end of the compartment.

100 2. A vertically arranged retort or still comprising an outer wall, a partition extending across the interior of the retort or still having openings and means for closing them, said partition separating the retort or 105 still into upper and lower compartments, heating pipes for heating the compartments, means for supplying a heating medium to the heating pipes of the different compartments independently, separate offtakes for the 110 products of distillation leading from the different compartments, the offtake for the lower compartment leading from near the partition at the upper end of the compartment, a second partition extending across the interior of the retort or still at the lower end of the lower compartment having openings and means for closing them, said second partition separating the lower compartment from a chamber below it, and means for 115 cooling said chamber.

120 3. A vertically arranged retort or still comprising an outer wall, a central tube, a partition surrounding the central tube and extending across the interior of the retort 125 or still having openings and means for

closing them, said partition separating the retort or still into upper and lower annular compartments, heating pipes for heating the compartments, means for supplying a heating medium to the heating pipes of the different compartments independently, and separate offtakes for the products of distil-
5 lation leading from the different compartments, the offtake for a lower compartment leading from near the partition at the upper 10 end of the compartment.

In testimony whereof I affix my signature this 19th day of January, 1918.

HUGH MACRAE.
